UNITED STATES PATENT OFFICE

JOHN HENRY FRIEDMAN, OF TIFFIN, OHIO, ASSIGNOR TO THE NATIONAL MACHINERY CO., OF TIFFIN, OHIO

METHOD OF AND MEANS FOR HANDLING CUT BLANKS FOR FORGINGS

Application filed November 14, 1929. Serial No. 407,256.

This invention relates to a method of and means for handling cut blanks used in the production of forgings.

Under some conditions it is most convenient to make forgings from cut blanks rather than from a bar of stock. However, there are many forgings which cannot be made from cut blanks because the means used for holding the blanks interferes with the flow of 10 the metal in the dies. It has been found that if sufficient clearance is cut in the dies for the tongs ordinarily employed, the metal will flow into this clearance and result in a defective forging.

15 It is an object of the present invention to provide simple and efficient means for holding a blank, the construction of this means being such as to permit the production of apertured forgings, undercut forgings, and 20 forgings of other types and shapes which could not be made heretofore from cut blanks.

With the foregoing and other objects in view which will appear as the description 25 proceeds, the invention consists of certain steps of the method and certain details of construction hereinafter more fully described and pointed out in the claims, it being understood that changes may be made in the 30 method and the apparatus used without departing from the invention as claimed.

In the accompanying drawings the invention has been clearly illustrated.

In said drawings, 35 Figure 1 is a view showing more or less in diagram a portion of a forging machine having the blank-holding means positioned therein.

Figure 2 is a side elevation of blank-holding tongs.

Figure 3 is an end view thereof.

Figure 4 is a side elevation of a modified form of tongs whereby a forging having an 45 annular rib or flange can be produced.

Figure 5 is an end view thereof.

Figure 6 is a section through a portion of the blank holder in position between the gripping dies, a blank being shown positioned 50 in the holder prior to being shaped by the

tool a portion of which has been illustrated in elevation.

Figure 7 is a view similar to Figure 6 showing the parts after the blank has been shaped.

Figure 8 is a view similar to Figure 7 showing how a blank may be shaped into a forging having a circular groove or the like in one end.

Figure 9 is a section through the gripping dies and the blank holder showing the structure used when it is desired to produce a pierced forging by means of a punch a portion of which has been shown in elevation in said figure.

Figure 10 is a view showing a portion of the structure illustrated in Figure 9 and illustrating how the piercing of the forging is completed.

In Figure 1 a portion of the bed of a forging machine has been indicated at 1 and the gripping dies of the machine have been illustrated at 2 and 3. The header slide has been shown at 4 and carries a tool 5 for working between the dies 2 and 3. The movable die 3 can be operated by any suitable mechanism indicated generally at 6. It is to be understood that in Figure 1 the parts of the machine have been indicated, to a certain extent, in diagram.

For the purpose of handling blanks tongs of special construction are provided. These tongs include opposed jaws 7 having arms 8 extending therefrom and pivotally connected as at 9. The gripping dies 2 and 3 are provided with any desired depressions 10 in which portions of the forgings can be shaped. The meeting faces of the dies 2 and 3 are also formed with clearances 11 and into these are adapted to fit snugly the outer faces of the jaws 7. The inner faces of the jaws are cut to form die spaces as shown at 12 so that the jaws 7 of the tongs are, in effect, dies in which a portion of a forging will be shaped.

In practice the heated blank is gripped at one end between the jaws 7 and placed between the gripping jaws 2 and 3 so that the said jaws 7 will be received within the clearances 11 and pressed firmly together when 100

ing a depression in that end of the blank housed between the jaws when the blank is subjected to longitudinal pressure.

5. The combination with the gripping dies of a forging machine, said dies having clearances therein, of tongs for feeding a blank thereto including jaws adapted to grip and house one end of the blank, said jaws being insertable between the gripping dies and 10 within the clearances, said gripping dies constituting means for holding the jaws pressed together and against axial movement, means movable between the gripping dies for shaping one end of a held blank against said 15 gripping dies and pressing the other end of the blank back between the jaws, and means on the jaws for recessing that end of the blank housed between the jaws when the blank is subjected to end pressure, said jaws 20 and recessing means, when released from the dies, being removable from the blank solely in a direction axial of the blank.

6. A means for handling and shaping short blanks including opposed relatively 25 movable jaws cooperating to provide a cavity extending thereto from one end, pivotally connected handles extending from the other end of the jaws, separable gripping dies recessed to receive and grip the closed 30 jaws, the handles of the gripped jaws projecting outwardly from the dies in position to be grasped and shifted by the operator, the cavity in the jaws constituting means for holding one end of a short blank with its 35 other end protruding from the jaws, and means for placing the blank under pressure to shape it within the cavity.

7. A means for handling and shaping short metal blanks including gripping dies having 40 recesses in the working faces thereof, opposed relatively movable jaws providing a cavity extending thereto from one end for the reception of one end of the blank, pivotally connected handles extending from the other 45 end of the jaws and adapted to be grasped by the operator to move the jaws into and out of position in the recesses in the faces of the dies, and pressure means for engaging the blank and shaping it between the jaws seated 50 in the recesses, the walls of the recesses cooperating with the jaws to hold said jaws against displacement in any direction relative to the dies when subjected to the action of the pressure means.

- 55 8. A means for producing a forging with a recessed end which comprises gripping dies adapted to be moved toward and from each other having recesses in the working faces thereof, relatively movable jaws removably seated in the recesses and held against longitudinal movement by the walls of the recesses, said jaws providing a cavity open at one end, a projection in the other end of the cavity extending toward the open end of the cavity, 60 pressure means working between the dies for

engaging one end of the blank and shaping the other end between the jaws and around the projection whereby the blank, while seated in the cavity, will lock the jaws against separation, and handles extending from the jaws adapted to be grasped by the operator to remove the jaws and blank from between the opened dies and release the shaped blank from the jaws.

9. A means for producing a forging with 75 a recessed end which comprises gripping dies adapted to be moved toward and from each other having recesses in the working faces thereof, relatively movable jaws removably seated in the recesses and held against longitudinal movement by the walls of the recesses, said jaws providing a cavity open at one end, a projection in the other end of the cavity extending toward the open end of the cavity, pressure means working between the dies for 80 engaging one end of the blank and shaping the other end between the jaws and around the projection whereby the blank, while seated in the cavity, will lock the jaws against separation, and means extending from the 85 jaws at that end thereof remote from the open end of the cavity, for removing the locked jaws from between the dies to permit release of the blank and jaws.

10. A means for producing a forging with 90 a recessed end which comprises gripping dies adapted to be moved toward and from each other having recesses in the working faces thereof, relatively movable jaws removably seated in the recesses and held against longitudinal movement by the walls of the recesses, said jaws providing a cavity open at one end, a projection in the other end of the cavity, extending toward the open end of the cavity, pressure means working between the dies for 95 engaging one end of the blank and shaping the other end between the jaws and around the projection whereby the blank, while seated in the cavity, will lock the jaws against separation, and means for removing the 100 locked jaws from between the dies to permit release of the blank and jaws.

11. A means for handling and shaping short blanks including opposed gripping dies providing a recess having a shoulder, blank-handling tongs having relatively movable jaws detachably seated in said recess and providing a cavity for housing one end of a blank the other end of which projects from the cavity, said jaws being shaped to receive end 105 thrust from the blank in the cavity, pressure means for shaping the projecting end of the blank against the dies and jaws and for shaping the housed end of the blank by extrusion within the cavity, the shoulder and jaws cooperating to hold the jaws against displacement relative to the gripping dies when subjected to the action of the pressure means.

12. Apparatus for producing from a short blank a forging with a depression in one end, 110

including separable movably connected jaws having a blank holding cavity open at one end and provided in its other end with a projection, dies movable to grip the jaws and hold them against movement relative thereto, and a heading tool movable between the gripping dies to engage one end of the held blank and shape the opposite end thereof about the projection in the cavity.

10 13. Apparatus for producing from a short blank a forging with a depression in one end, including separable movably connected jaws having a blank holding cavity open at one end and closed at its other end, means on the 15 respective jaws cooperating to provide a projection in the cavity at the closed end thereof, dies movable to grip the jaws and hold them against movement relative thereto, and a heading tool movable between the gripping dies to engage one end of the held blank and 20 shape the opposite end thereof about the projection in the cavity.

In testimony that I claim the foregoing as my own, I have hereto affixed my signature.
